TRANSFORMER SYSTEM

Albert E. Feinberg, Chicago, Ill., assignor to
Advance Transformer Co., Chicago, Ill., a cor-
poration of Illinois

Application March 3, 1947, Serial No. 731,991

5 Claims. (CL 323—61)

1

This invention relates to transformers, and more particularly to a transformer for operating a plurality of hot cathode glow discharge tubes, such as fluorescent tube lamps.

In order to improve the power factor of lighting circuits in fluorescent tube lamps, and for other desirable purposes, it has been customary to operate the tubes in pairs off of a single transformer. The transformer has a primary winding and a pair of secondaries, one for each fluorescent tube, the secondaries being connected in step-up auto transformer relationship with the primary. A condenser is provided in series with only one of the tubes and of sufficient capacity to cause that tube to draw a leading current to compensate for the lagging current taken by the other tube.

Fluorescent lamps of the hot cathode type are started by providing a temporary series connection between the filaments at the opposite ends of the tube. In starting two lamps which are operated from a single transformer in a circuit as above set forth it has been found that the condenser in series with one of the lamps in many instances reduces the current flowing to that lamp to an undesirable amount. In addition, in many instances there is sufficient intercoupling within the secondary coils of the transformer so that a reduction of the current flowing in that secondary which is in series with the condenser results in an increase of the current flowing in the other secondary which is connected to the other lamp. Thus the condenser not only diminishes the amount of current flowing to one of the lamps but frequently also increases the amount of current flowing to the other lamp, both changes being to undesirable degrees. The resulting voltages across the lamps are also changed.

It is one of the objects of the present invention to provide an improved transformer structure and circuit arrangement wherein the current wave of the leading lamp is substantially sinusoidal, thereby eliminating the third harmonic which is otherwise frequently present in the wave form. It is a further object of the present invention to provide a transformer of the above mentioned character wherein the circuit arrangement is such as to permit a much lower saturation of the iron core and therefore a correspondingly lower maximum temperature rise in the iron. It is a still further object of the present invention to provide a circuit arrangement wherein the secondary requires a lower flux

2

density thereby permitting a diminution in the number of turns on the core.

The attainment of the above and further objects of the present invention will be apparent from the following specification taken in conjunction with the accompanying drawing forming a part thereof.

In the drawing:

Figure 1 is a diagrammatic circuit arrangement illustrating the present invention; and

Figure 2 is a similar circuit arrangement illustrating a modified arrangement.

Reference may now be had more particularly to the drawings wherein like reference numerals 15 designate like parts throughout.

In Figure 1 there is shown a transformer 1 comprising an iron core formed of a stack of L-shaped laminations assembled through six similar (but not identical) coils. Each lamination 20 includes a long leg 2 and a short leg 3, the laminations being assembled so that the abutments 4 between adjacent laminations in the same layer are at the opposite corners of a rectangle, and with the abutments 4 of adjacent layers staggered 25 at opposite sets of corners of the rectangle. The transformer of Figure 1 includes a pair of series connected primary coils 6 and 7, a pair of series connected secondary coils 8 and 9 which will ultimately supply the leading current, and another pair of series connected secondary coils 10 and 11 which will ultimately supply the lagging current. The two coils 6 and 7 will hereinafter be referred to as the primary, the two coils 8 and 9 will hereinafter be referred to as a secondary 30 and the two coils 10 and 11 will hereinafter be referred to as another secondary. Each secondary is connected in step-up auto transformer relationship to the primary. The secondary 10—11 is connected through a lead 15 to one side 35 of a filament 16 of a hot cathode glow discharge tube 18, of the fluorescent type. The other side of the filament 16 is connected through a starter 19 to one side of a filament 20 of the lamp 18. The other side of the filament 20 is connected to one line of the source of power 21. The secondary 8—9 is connected through a lead 25 to the winding 26 of an iron core reactance from which the circuit is extended through a condenser 27 to one side of a filament 28 of the leading lamp 50 29, which is also of the hot cathode glow discharge type, preferably a fluorescent lamp. The other side of the filament 28 is connected to a starter 30, preferably, although not necessarily, in series with a compensating winding 31 and 55 then connected to the opposite filament 33 of the

lamp 29, that filament being also connected to the line 21.

In the construction herein shown the primary coils 6-7 are located as close as possible to the secondary coils 8 and 9 and as far as possible from the secondary coils 10 and 11. In one preferred construction involving a transformer for use on a 118 volt 60 cycle line with two tubes each of 40 watts, each of the primary coils was two inches long and contained nine hundred turns. Each of the secondary coils was one and nine-sixteenths inches long and contained seven hundred sixty turns. The coil 26 contained five hundred turns and the compensating winding 31 contained three hundred fifty turns. The windings 26 and 31 were connected in cumulative series during starting to constitute a step-up transformer. When the starting switch 30 opens its circuit the compensating winding 31 is, of course, open circuited.

In the circuit of Figure 1 the secondary 10-11 is loosely coupled with the primary so that there is sufficient leakage reactance to limit the current flowing to the lamp 18, during starting, to its correct operating value. The secondary 8-9 being close to the primary has insufficient leakage reactance to supply the proper operating current to the lamp 29 when used in series with the condenser 27 which is of a size such that the capacitative reactance of the condenser is substantially greater than the inductive reactance of the windings 8-9. The reactor 26 is of such a value that during operation the sum of the reactance 26 plus the reactance of the coils 8-9, in relation to the capacity reactance 27, is of the correct value in relation to the open circuit voltage and lamp impedance to supply the proper operating current to the lamp. The effect of the reactance 26 is to correct the crest factor of the current in the lamp 29 to a much lower value than can be obtained without it.

As a result of the circuit arrangement shown in Figure 1 the current wave form of the leading lamp 29 is essentially sinusoidal, and the watt output of that lamp is raised thereby permitting a decrease in the current flowing therethrough. The elimination of the third harmonic in the wave form and the reduction of the leakage reactance of the secondary 8-9 results in a much lower saturation of the iron core and correspondingly a much lower temperature rise in the iron. Furthermore, due to the lower flux density required in the coils 8-9 it has been found possible to reduce considerably the number of turns in the other coils on the core, resulting in a still further decrease in heating and a saving in copper. The compensating winding 31 may be wound on the same iron core as carries the winding 26, or the compensating winding 31 may be on a different iron core.

The effect of the reactance 26 during starting is substantially greater than it is during operation, by reason of the fact that during starting the compensating winding 31 is in the circuit whereas during operation the compensating winding 31 is not in the circuit.

The transformer 1 and the reactances 26 and 31 and the condenser 27 are all located in a single container or can from which extend the various connecting leads for the external circuit. This includes the leads that connect to the line 21, the lead 15, the two leads from the reactance 31, and the lead from the condenser 27 that is to be connected to the filament 28. By this arrangement the circuit connections to the two lamps 18

and 29 can be made as shown, whereby the reactance 31 may selectively be connected in circuit or disconnected from the circuit, depending upon whether or not the starter switch 30 is closed or open.

In Figure 2 I have shown a circuit arrangement substantially the same as that in Figure 1, differing therefrom only in that the positions of the coils 7 and 9 have been interchanged. In other respects the two circuits are the same.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

20. 1. Apparatus for supplying a plurality of separately operable hot cathode glow discharge devices with leading and lagging currents respectively comprising an elongated core, a primary positioned on said core intermediate the ends 25 thereof, a pair of secondaries positioned on the core one at each end thereof, each of the secondaries being connected to the primary to form a step-up auto transformer, the primary being substantially closer to one of the secondaries than 30 to the other secondary, a condenser in series with the secondary that is closest to the primary, and a two coil inductance with the coils thereof inductively coupled together and separate leads extending from the respective coils of the two 35 coil inductance to permit selective connection of one or both of the two coils of the inductance in series with one another and with the secondary coil that is closest to the primary.

2. Apparatus for operating two hot cathode 40 discharge tube loads, comprising a transformer having a two coil primary winding, a leading secondary winding having two coils, a lagging secondary winding having two coils spaced from the primary and less closely coupled thereto than 45 is the first secondary, a core for said windings, said core being of an elongated rectangular shape one coil of each of the three windings being on one longitudinal side of the core and the other coil of each winding being on the other longitudinal side of the core, leads from the respective secondaries for individual connection to different tube circuits, a condenser in the circuit of the lead from the leading secondary, and a two coil reactor having an iron core separate from the 50 aforementioned rectangular core and magnetically coupling the coils of the reactor, one of the reactor coils being connected in series circuit with the condenser and the leading secondary and the other reactor coil having conductor leads 55 therefrom for permitting the selective connection thereof into said series circuit during starting of the tubes and out of said series circuit during operation of the tubes, so that the value of the reactance may be changed as the associated tube 60 changes from starting condition to operating condition.

3. Apparatus for operating two hot cathode 65 discharge tube loads comprising a transformer having a primary, a first secondary, a second secondary spaced from the primary and less closely coupled thereto than is the first mentioned secondary, both secondaries being electrically connected to the primary in step-up auto-transformer relationship, said transformer having a rectangular core including opposite longi-

tudinal sides joined by transverse ends, said secondaries and said primary each comprising two series connected coils one on each of the two opposite longitudinally extending sides of the core, leads from the respective secondaries for individual connection to different tube circuits, a reactor coil and a condenser in series and connected in series with a lead from the first secondary, said reactor coil having an iron core and being outside of the magnetic circuit of the transformer, an additional coil on said last mentioned iron core and magnetically coupled to the reactor coil, and leads from the additional reactor coil for selectively connecting and disconnecting the additional coil in series with the first reactor coil.

4. Apparatus for operating filament heater type leading and lagging hot cathode discharge tube loads comprising a transformer having a primary, a first secondary, a second secondary spaced from the primary and less closely coupled thereto than is the first mentioned secondary, both secondaries being electrically connected to the primary in step-up auto transformer relationship, said transformer having a rectangular core including opposite longitudinal sides joined by transverse ends, said secondaries and said primary each comprising two series connected coils one on each of the two opposite longitudinally extending sides of the core, leads from the respective secondaries for individual connection to different tube circuits, a reactor coil and a condenser in series and connected in series with a lead from the first secondary, said reactor coil

having an iron core and being outside of the magnetic circuit of the transformer, an additional coil on said last mentioned iron core and magnetically coupled to the reactor coil, a starter switch in the circuit of the leading tube with the condenser, and circuit connections including said switch and said additional coil in circuit between the heating filaments of said last mentioned tube and open circuiting said additional coil upon opening of the starting circuit of said last mentioned tube.

5. Apparatus such as defined in claim 2 wherein the two primary coils and the two leading secondary coils are adjacent one another and with one of the primary coils adjacent an end of one longitudinal side of the transformer core and one leading secondary coil adjacent the corresponding end of the other longitudinal side of the transformer core.
